UNITED STATES PATENT OFFICE.

FREDERICK WESTERBECK, OF ST. LOUIS, MISSOURI.

SHEET-METAL CAN.

Application filed December 12, 1921. Serial No. 521,644.

To all whom it may concern:

Be it known that I, FREDERICK WESTERBECK, a citizen of the United States of America, a resident of the city of St. Louis and State of Missouri, have invented certain new and useful Improvements in Sheet-Metal Cans, of which the following is a full, clear, and exact description, reference being had to the accompanying drawings, forming a part of this specification.

This invention relates to improvements in sheet metal cans, and more particularly to a can adapted to receive closure-removing tool whereby the closure can be easily forced from the can body. The main object is to produce a very strong can of this kind having its elements arranged to provide an effective seal between the closure and the can body. By bending the sheet metal as will be hereinafter described, I produce reinforcing elements which very effectively strengthen the closure and can body, so these parts can be made of very thin, inexpensive sheet metal. The closure has a marginal flange which forms a seal outside of the can, and a portion of this flange is bent upwardly and folded to produce a strong tool-receiving member, which lies entirely above the upper edge of the can to provide a space for a closure-removing tool.

Fig. I is a side elevation of a can embodying the features of this invention.

Fig. II is a top view of a portion of the can showing the part of the closure to which the closure-removing tool is applied.

Fig. III is an enlarged fragmentary section on the line III—III in Fig. I.

Fig. IV is an enlarged fragmentary section on the line IV—IV in Fig. I.

A designates a sheet metal can body, and B designates a closure applied to said body. The upper margin of the can body is curled inwardly to form an internal annular bead 1 within the can body, said bead being substantially circular in cross section. The edge of the metal forming the bead is preferably separated from the side wall of the can, as shown in Figs. III and IV, so as to permit the bead to yield and conform to the seats on the closure.

The closure may be provided with a central portion 2 pressed upwardly from a flat, horizontal web 3 (Figs. II and III) and a marginal portion embracing and closely fitted to the annular bead 1, to form a seal between the closure and the can body. More

specifically stated, the closure has an annular sealing web 4 engaging the inner side of the annular bead 1 to form an annular seal inside of the can. This sealing web 4 extends downwardly from the bead 1 to the flat web 3. The closure is provided with a marginal flange having a 2-ply downturned portion 5 engaging the outer side of the bead 1 and a relatively stiff, outwardly extending portion 5' having a plurality of folds (Figs. I and IV) merging into said downturned portion. The outwardly extending portion 5' of the marginal flange is folded, as shown most clearly by Fig. IV, and this portion is located entirely above and separated from the top of the annular bead 1, so as to provide an open space for a closure-removing tool. There are four thicknesses of metal in the folded portion 5' of the marginal flange (Fig. IV), and these folds merge into the 2-ply downturned portion 5 of the marginal flange. This produces an extremely strong and rigid portion well adapted to receive a screw driver, or other suitable tool, which is inserted between the portion 5' and the top of the strong bead 1 to force the closure from the can body.

As shown most clearly by Fig. III, the closure embraces the annular bead 1 to form seals at the inner and outer sides of said bead, and Fig. IV shows that the folded portion 5' of the closure is formed by metal which extends upwardly and outwardly from the annular sealing web 4. However, the sealing web 4 cooperates with the inner side of bead 1 to form a continuous annular seal, which is not impaired by the outwardly extending folded portion 5'.

The downturned portion 5 of the marginal flange extends almost entirely around the can, and the yieldable bead 1 is confined under pressure between said downturned portion and the sealing web 4, so a very effective seal is produced between the closure and the bead. Furthermore, although the can and closure may be made of extremely thin sheet metal, they will not be torn or mutilated by a closure-removing tool between the outwardly extending folded portion 5' and the bead 1. The stresses resulting from an upward thrust of the tool will be primarily borne by the folded portion 5' and the bead 1, and these stresses will be transmitted from said folded portion to the downturned 2-ply portion of the marginal closure flange.

I claim:

1. A sheet metal can having an internal annular closure seat on the inner face of its upper edge, and a closure embracing said upper edge, said closure having an annular sealing web engaging said internal annular seat to form a seal inside of the can, said closure also having a marginal flange provided with a downturned portion engaging the outer side face of the can and an outwardly extending portion located above the upper edge of the can to receive a closure-removing tool.
2. A sheet metal can having an internal annular closure seat on the inner face of its upper edge, and a closure embracing said upper edge, said closure having an annular sealing web engaging said internal annular seat to form a seal inside of the can, said closure also having a marginal flange provided with a downturned portion engaging the outer side face of the can and a relatively stiff outwardly extending portion folded on itself and located entirely above the upper edge of the can to receive a closure-removing tool.
3. A sheet metal can having an internal annular closure seat on the inner face of its upper edge, and a closure embracing said upper edge, said closure having an annular sealing web engaging said internal annular seat to form a seal inside of the can, said closure also having a marginal flange provided with a two-ply downturned portion engaging the outer side face of the can and a relatively stiff outwardly extending portion having a plurality of folds merging into said two-ply downturned portion, and said outwardly extending portion being located entirely above the upper edge of the can to receive a closure-removing tool.
4. A sheet metal can having an internal annular closure seat on the inner face of its upper edge and an external annular closure seat surrounding said internal seat, and a

closure having an annular sealing web engaging said internal annular seat to form an annular seal inside of the can, said closure also having a downturned marginal flange engaging said external annular seat to form a seal outside of the can, and a portion of said marginal flange being bent upwardly so as to lie entirely above said upper edge of the can for the purpose set forth.

5. A sheet metal can having an internal annular bead at its upper edge, and a closure embracing said internal annular bead, said closure having a downturned marginal flange engaging the outer face of said annular bead, and a downturned annular web engaging the inner face of said annular bead to form an annular seal inside of the can, a portion of said marginal flange being bent upwardly and extended outwardly from said annular web so as to lie entirely above said annular bead, and said portion being separated from the top of said annular bead to provide a space for a closure-removing tool.

6. A sheet metal can having an internal annular bead at its upper edge, and a closure embracing said internal annular bead, said closure having an annular sealing web engaging the inner side of said annular bead to form an annular seal inside of the can, said closure also having a marginal flange provided with a two-ply downturned portion engaging the outer side face of said annular bead, and a relatively stiff outwardly extending portion having a plurality of folds merging into said two-ply downturned portion, said outwardly extending portion being located entirely above and separated from the top of said annular bead to provide an open space for a closure-removing tool.

In testimony that I claim the foregoing I hereunto affix my signature.

FREDERICK WESTERBECK.
